(57) **CLAIM**

The ornamental design for a contact lens case, as shown and described.

DESCRIPTION

FIG. 1 is a perspective view of a contact lens case showing our new design;

FIG. 2 is a front view thereof;

FIG. 3 is a rear view thereof;

FIG. 4 is a right side elevational view thereof;

FIG. 5 is a left side elevational view thereof;

FIG. 6 is a top plan view thereof; and,

FIG. 7 is a bottom plan view thereof.

The broken line showing an aperture on the tab of the case in FIGS. 1, 6, & 7 represent an internal boundary of the design with the broken line and the area within forming no part of the claim.

1 Claim, 4 Drawing Sheets**FIG. 1**

FIG. 2

FIG. 3

FIG. 4**FIG. 5**

FIG. 6

FIG. 7
